UNITED STATES PATENT OFFICE.

ERNEST N. JOHNSON, OF WINNIPEG, MANITOBA, CANADA.

RAIL ANCHOR.

Application filed March 28, 1927. Serial No. 179,083.

The invention relates to improvements in rail anchors and an object of the invention is to provide a device which will positively prevent a track rail from creeping and which is 5 arranged so that when installing one can readily reverse it depending on the direction which it is found that the rail has a tendency to creep.

A further object is to construct the device 10 in a simple and durable manner, so that replacements can be easily, quickly and cheaply made and such that it in no way interferes with the customary spikes utilized to hold the rail to the ties.

15 With the above more important objects in view, the invention consists essentially in the arrangement and construction of parts hereinafter more particularly described, reference being had to the accompanying drawing, 20 in which:—

Fig. 1 is a plan view of a portion of a rail showing one of my devices provided thereon.

Fig. 2 is a plan view of a portion of a rail and showing two of my devices applied 25 thereon to prevent creeping in either direction.

Fig. 3 is an enlarged detailed plan view of the device and adjoining portion of the rail.

Fig. 4 is an inverted plan view of the device.

Fig. 5 is a vertical sectional view at 5—5' Figure 3 and looking in the direction of the applied arrow.

Fig. 6 is a perspective view of the cover.

35 In the drawing like characters of reference indicate corresponding parts in the several figures.

The track rail 1 is carried by the tie plates 2 which are mounted on the customary ties 3. 40 The usual spikes 4 and 5 are employed to hold the rail to the tie, these being driven into the tie through suitable holes provided in the plate.

Under existing traffic and other conditions, 45 if it is found that a rail creeps in one direction only, such as in the direction of the applied arrow Figure 1, I use one of my devices which would be located on the central tie of those carrying the rail and would have the 50 device set as later explained to prevent the creeping of the rail in the direction indicated Figure 1. Where a rail may creep in either direction as indicated by the applied arrow Figure 2, I will place two of my devices on 55 the two ties nearest the centre of the rail, such as shown in Figure 2 and will set the

device to prevent creeping in either direction.

As herein shown, the tie plate 2 carrying my device is in the nature of a substantially rectangular plate provided at the inner end with an upstanding stop flange 6 adapted to 60 engage the inner edge of the rail base when the rail is in position. The plate is provided also with pairs of spike holes 7 located in the usual position adjacent the inner and outer edges of the rail base and the customary angularly positioned spikes 4 and 5 are driven into the tie through the holes and have the heads thereof overlying the base of the rail as shown.

65 In a location intermediately between the pair of spike holes at the outer side of the rail, I locate an upstanding stud 10 which is positioned somewhat further out from the rail base than the spike holes and is carried by the tie plate. On this stud, I mount rotatably a dog 11 which is provided with a circular hole 12 to receive the stud. The dog is designed to engage the adjacent edge of the rail base and has the engaging end thereof 70 presenting a toothed face 13 which is formed eccentric to the vertical axis of the stud. The length of the dog is such that it will always maintain an angularly disposed position in respect to the rail, that is to say, the longitudinal axis of the dog will not at any time be 75 able to take a position at right angles to the longitudinal axis of the rail.

80 A cover 14 is provided to enclose the greater part of the dog, the cover being made from a substantially rectangular plate having the corners cut away as indicated at 15 and 16 to clear the spikes and the uncut sides and outer edge fitted with a continuous down-turned flange 17. Centrally the cover is provided with a built up collar 18 and an opening 19 passing therethrough which receives the upper end of the stud. The upper end of the stud is provided with a hole 20 and the upper face of the collar is fitted with radiating slots 21. A cotter pin 22 is passed 85 through the hole in the stud and lies in the slots. The dog is also cross slotted as indicated at 11' to receive one end of a flat spring 23, the other end of which is adapted to engage the inner face of the flange 17.

100 When it is desired to prevent creeping of the rail in the direction of the applied arrow in Figure 1, the dog is placed on the stud in the position shown in Figure 3, it being of course understood that the cotter pin and 105 the cover have been previously removed. At 110

- this time, the spring will be extending as shown at A in dotted outline in Figure 3. One then applies the cover and in applying it, catches the free end of the spring behind the flange 17 and after having caught it, rotates the cover into the position shown in Figure 3. This movement will bring the spring into the position shown at B Figure 3 where it is in tension and is accordingly acting to swing the dog towards the previously inserted rail base. Whilst one is holding the cover in the position shown, the cotter pin is passed through the slots and hole 20 and locks the cover against rotation.
- 15 With the device so set it will be apparent that any tendency of the rail to creep from left to right will be counteracted by the jamming action effected between the stop flange 6 and the dog.
- 20 If it is desired to prevent creeping of the rail in the opposite direction to that just described, the dog is put in place in the reverse position as will be readily understood. The arrangement of the anchor is such that the
- 25 rail can be readily put in place on the tie plate as the cover is not applied until after the rail has been set on the plate and under such condition, the spring is inactive so that the dog can be moved out to clear the rail.
- 30 Further all parts are arranged so that the spring can be readily replaced should it fail through continued use. Another important feature is that the dog can be set to prevent creeping of the rail in either direction.
- 35 Whilst I have shown the dog as carried by a tie plate, it is to be understood that it could be mounted on the well known type of rail anchor and will act with equal effect to prevent end shifting or creeping of the rail.
- 40 What I claim as my invention is:—
1. The combination with the base of a rail, a tie plate supporting the same, said plate being provided with a stop shoulder engaging one edge of the rail base, of an upstanding stud permanently attached to the plate and positioned somewhat back from the other

edge of the rail base, a dog pivotally mounted on the stud and presenting a toothed face engageable with the latter edge of the rail and formed eccentric to the stud, a cover overlying the dog, a spring extending between the cover and the dog and holding the dog normally engaged with the rail base and a pin fastening the cover to the stud.

2. The combination with the base of a rail, a tie plate supporting the same, said plate being provided with a stop shoulder engaging one edge of the rail base, of an upstanding stud carried by the plate and positioned somewhat back from the other edge of the rail base, a dog pivotally mounted on the stud and presenting a toothed face engageable with the latter edge of the rail and formed eccentric to the stud, a cover overlying the dog and pivotally mounted on the upper end of the stud and provided with a marginal flange, a spring carried by the dog and engageable with the flange and a withdrawable locking pin fastening the cover to the stud.

3. The combination with the base of a rail, of a tie plate supporting the rail base and provided at the inner end with an upstanding stop shoulder engageable with one edge of the rail base and with suitably located spike holes, an upstanding stud carried by the plate in a location adjoining to but somewhat back from the other edge of the rail base, a reversible dog pivotally mounted on the stud and provided with a toothed face engageable with the latter edge of the rail base and formed eccentric to the stud, a cover overlying the dog and provided with an opening to rotatably receive the upper end of the stud and with a marginal flange, a flat spring carried by the dog and engageable with the flange and normally pressing the dog towards the rail and a withdrawable pin fastening the cover to the stud.

Signed at Winnipeg, this 5th day of March, 1927.

ERNEST N. JOHNSON.
